UNITED STATES PATENT OFFICE.

GEORGE FEATHERSTONE SHIMMIN, OF MARYPORT, ENGLAND.

SPRING-FORK FOR CYCLES, MOTOR-CYCLES, AND THE LIKE.

1,166,156.

Specification of Letters Patent. Patented Dec. 28, 1915.

Application filed January 12, 1914. Serial No. 811,635.

To all whom it may concern:

Be it known that I, GEORGE FEATHERSTONE SHIMMIN, a subject of the King of the United Kingdom of Great Britain and Ireland, and resident of Maryport, England, have invented a certain new and useful Improvement in Spring-Forks for Cycles, Motor-Cycles, and the like, of which the following is a specification.

10 This invention relates to improvements in spring forks for cycles, motor-cycles and the like, and has for its object to provide a construction of spring forks in which is combined with the usual rigid forks a system of 15 linked levers or toggles and main and rebound springs.

In the accompanying drawings illustrating the invention, Figure 1 is a side elevation of one form of the improved spring fork; Figs. 2 and 3 are respectively a front elevation and a side elevation partly in section of a slightly modified construction; and Fig. 4 is a plan, partly in section, showing an alternative arrangement.

25 In accordance with the invention, and as represented in the accompanying drawings illustrating the improved spring forks as applied to a motor-cycle, the said forks comprise in combination with the usual curved 30 rigid forks A of the machine frame as shown at Fig. 3, or with fork bars A' bolted to the usual stem tube E as shown at Fig. 1, short levers B pivoted at the lower ends of these forks and supporting the front wheel axle.

35 Through said levers B pressure due to the weight of the fore-part of the machine is transmitted to two pairs of compression rods or toggles C, D, one pair C of which is connected to the levers B while each member of 40 the other pair D is hingedly connected at its upper end to the stem tube or stem-tube fitting E' of the rigid fork A as indicated at Fig. 3 or to the upper end E' of an upward extension of the fork bars A' as indicated at

45 Fig. 1. The point of connection at f of each pair of compression rods C, D, is movable relatively to the stem-tube and is resiliently connected thereto by means of a rod I provided with combined main and rebound 50 springs G, G' (not shown in Figs. 3 and 2). These springs G, G', may be fitted, as shown at Fig. 1 on telescopic tubular guides g, g' fitted in a swiveling crosshead H at the joint f connecting the rods C, D, while the 55 rod I jointed to a cross-piece J between the forks A' extends through the tubular guides

and is held by nuts bearing on a cap K on the outer end of the tubular guide g'. The spring G is held normally in compression between a flange at one end of the guide g bearing on the swiveling crosshead H, and the flanged end of a block L on which the guide g is free to slide; while the spring G' is held between a flange engaging the swiveling crosshead H and a flange on the outer 65 end of the tubular guide g' so that it is held normally under compression.

In an alternative arrangement as shown in Fig. 4 there is substituted for the spring G' a pair of tension springs O, O arranged 70 one on each side of the spring G, each attached at one end to the bracket M secured to said rigid fork A or A' and at the other to the swiveling crosshead H connecting the rods C, D, or as shown, to the ends of a 75 rocker N pivoted at Q on a bracket R connected to or formed integral with said crosshead H, so as to maintain equal pressure on each spring O.

The short levers B above referred to may 80 be arranged to project either rearwardly or forwardly of the ordinary rigid forks A or A' as shown in Figs. 1 and 3. In the latter case, the device can be more easily applied to slightly curved, or straight forks, as fitted 85 to some makes of motor-cycles and the like. The improved spring fork arrangement is also applicable to some makes of cycle car.

Having now described my invention, I declare that what I claim and desire to secure 90 by Letters Patent of the United States is:

1. In a spring fork device for the front wheel of a cycle, in combination with a rigid bifurcated member, downwardly extending rods each having an articulated connection 95 with the upper end of said bifurcated member, two levers one pivotally connected to the lower end of each tine of said bifurcated member, said levers formed for attachment to the wheel spindle, a pair of upwardly extending rods one pivotally connected at its lower end to each of said levers and at its upper end with the lower extremity of each of said downwardly extending rods, the connection of said sets of 100 rods affording a toggle joint, and a main and rebound spring means connecting said connection and said bifurcated member.

2. In a spring fork device for the front wheel of a cycle, in combination with a 110 rigid bifurcated member, downwardly extending rods each having an articulated

connection with the upper end of said bifurcated member, two levers one pivotally connected to the lower end of each tine of said bifurcated member, said levers formed 5 for attachment to the wheel spindle, a pair of upwardly extending rods one pivotally connected at its lower end to each of said levers and at its upper end with the lower 10 extremity of each of said downwardly extending rods, the connection of said sets of rods affording a toggle joint, a spring interposed between said joint and said bifurcated member; a crosshead, a bracket on said crosshead, a lever pivoted centrally to said bracket, and springs interposed between the 15 ends of said last mentioned lever and said bifurcated member.

3. In a spring fork device for the front wheel of a cycle, the combination, with a 20 rigid bifurcated member, of two levers one pivotally connected to the lower end of each tine of the bifurcated member, said levers formed for attachment to the wheel spindle; a pair of downwardly extending rods 25 pivotally connected, for angular movement, at their upper ends to the upper part of the bifurcated member; a pair of upwardly extended rods pivotally connected respectively, at their lower ends, with said levers,

and at their upper ends with the lower ends 30 of said downwardly extending rods, whereby a toggle joint is formed; and a spring connecting said joint and said member.

4. In a spring fork device for the front wheel of a cycle, the combination, with a 35 rigid bifurcated member, of two levers one pivotally connected to the lower end of each tine of the bifurcated member, said levers formed for attachment to the wheel spindle; a pair of downwardly extending rods 40 pivotally connected, for angular movement, at their upper ends to the upper part of the bifurcated member; a pair of upwardly extending rods pivotally connected respectively, at their lower ends, with said levers, and at their upper ends with the lower 45 ends of said downwardly extending rods, whereby a toggle joint is formed; and a main and rebound spring connecting said joint and member.

In testimony whereof I have signed my name to this specification in the presence of two subscribing witnesses.

GEORGE FEATHERSTONE SHIMMIN.
